M. R. BERGER

GUTTER HANGER CIRCLE

Filed May 13, 1925

Fig. 1.

Inventor

Matthew Russell Berger

By William J. Jackson

Attorney

UNITED STATES PATENT OFFICE.

MATTHEW RUSSELL BERGER, OF PHILADELPHIA, PENNSYLVANIA.

GUTTER-HANGER CIRCLE.

Application filed May 13, 1925. Serial No. 29,637.

To all whom it may concern:

Be it known that I, MATTHEW RUSSELL BERGER, a citizen of the United States, residing at Philadelphia, in the county of Philadelphia and State of Pennsylvania, have invented a certain new and useful Gutter-Hanger Circle, of which the following is a specification.

This invention, generally stated, relates to gutter hanger circles and has more especial relation to that type of circle arranged for adjustable engagement with a shank of channel-bar formation.

As generally practiced it is now customary to stamp a circle from a single sheet of wrought iron, for instance of the type shown in my Letters Patent No. 1,368,539, dated Feb. 15, 1921. However, by this means a great waste of material ensues, and the finished circle is not as efficient as desired in that it may become distorted by workmen in installation. That is, a circle may be bent laterally considered.

Therefore, one object of the present invention may be said to reside in the provision of an adjustable gutter hanger circle of integral structure made from stock wrought metal for instance iron of T-shaped cross-section in order to reduce cost of production. Another object is to provide a circle of the character stated which will materially resist lateral distortion and provide a generally stronger circle. Still another object is to provide a circle of the character stated the web of which has a heel portion provided with an apertured rib the web top being sheared off and the flanged part of the rib being bent inwardly to form a gutter catch.

Still another object is to provide a circle of the character stated in which a relatively broad, shank bearing surface is provided adjacent the heel portion of the circle so that the circle in adjusted position may be more rigidly sustained.

Other and further objects not at this time appearing will be hereinafter referred to.

The invention consists of the novel construction hereinafter described and finally claimed.

The nature, characteristic features and scope of the invention will be more fully understood from the following description taken in connection with the accompanying

drawings forming part hereof, and in 55 which:

Fig. 1, is a view in side elevation of a circle of the invention shown as attached to a shank.

Fig. 2, is a view in cross-section taken 60 upon the line 2—2 of Fig. 1.

Fig. 3, is a view in section taken upon the line 3—3 of Fig. 2.

Fig. 4 is a view in side elevation of a 65 slightly modified form of circle; and

Fig. 5, is a view in section taken upon the line 5—5 of Fig. 4.

For the purpose of illustrating my invention I have shown in the accompanying drawings two forms thereof which are at 70 present preferred by me, since the same have been found in practice to give satisfactory and reliable results, although it is to be understood that the various instrumentalities of which my invention consists can be 75 variously arranged and organized and that my invention is not limited to the precise arrangement and organization of the instrumentalities as herein shown and described.

Referring to the drawings in detail and 80 with more especial relation to Figs. 1 to 3 inclusive, the numeral 1 designates a gutter hanger circle made in one piece from stock T-iron, or copper or brass and comprised of a vertical web 2 and a horizontal gutter-seat 3

extending at right angles to the web and upon opposite sides thereof. The outer end of the web is provided with a hook-shaped catch 4 and the opposite or heel portion of the web is apertured as at 5. The extreme 90 end of the heel is sheared off at 6 and that part of the gutter seat remaining is bent over to form a catch 7. In practice the heel

of the circle is arranged perpendicularly, as 95 designated by numeral 8. That part of the circle web which constitutes the circle heel has formed thereon a vertical rib 9. By this construction it is seen that upon one side of the web forming the circle heel there is provided a relatively broad bearing surface 100 designated 10 as formed by the perpendicular part of the gutter seat immediately adjacent the circle heel. The purpose of this bearing surface will presently appear.

The shank to which a circle of the above 105 type may be readily attached is disclosed in Figs. 1, 2, and 3, is made of channel-bar and designated 11. It is apertured at

12 to correspond with the apertures in the heel of the circle, receives the rib of the circle and the two are secured together by a bolt 13 in desired adjusted position. The 5 top of the shank is provided with a fastening plate 14. This type of shank forms subject matter of Letters Patent granted to me under date of September 19, 1922, and is numbered 1,429,482. However, my novel 10 form of circle is capable of use with different forms of shanks, the type disclosed being for illustrative purposes. It is seen that with the rib of the circle accommodated within the channel-bar forming the shank 15 that the bearing surface of the heel of the circle previously described abuts against the outer perpendicular edge 15 of the shank, see Fig. 2. This provides a very efficient attachment and tends to prevent sagging of 20 the circle which is most important. It is readily apparent that without this bearing surface there is a tendency for a circle, under weight of a gutter, to sag by moving around the pivot point formed by the securing bolt. 25 This my novel form of seating parts overcomes. Also, in installation workman cannot distort the circle because of its great strength which is another important factor.

For some types of gutters it is necessary 30 to have the gutter catch in a position lower than that disclosed in Fig. 1. Such a structure is shown in Figs. 4 and 5 wherein the flanged parts of the heel has struck out therefrom a pair of gutter catches designated 35 16 although obviously I may only provide one such catch. It is of course understood that with the gutter catches so arranged shearing off of the heel top is dispensed with.

40 It will now be apparent that I have devised a novel and useful construction which embodies the features of advantage enumerated as desirable in the statement of the invention and the above description and 45 while I have in the present instance shown and described the preferred embodiments

thereof which have been found in practice to give satisfactory and reliable results, it is to be understood that the same are susceptible of modification in various particulars without departing from the spirit or scope of the invention or sacrificing any of its advantages. 50

What I claim is:

1. A gutter-hanger circle comprising an 55 integral structure formed from wrought metal of T-shaped cross-section bent to form a web having extended from each side thereof a flanged part forming a gutter seat, the heel part of which is perpendicularly 60 arranged, a rib bent out from the heel part of said web said rib being apertured, and a gutter catch bent out from the circle heel at its top said catch being formed by first 65 shearing off the top of said web and then forming the catch from the part remaining.

2. In a gutter hanger, an apertured shank of channel-bar including its complement fastening device, one piece circle 70 formed of wrought metal of T-shaped cross-section, the heel part of which circle is perpendicularly arranged and provided with a rib for engaging in said channel-bar, said rib being apertured in register with the 75 apertures of said shank, and a bolt for securing the circle and shank together, the heel of said circle having a relatively broad bearing surface for abutting against the outer face of said shank.

3. A gutter hanger circle comprising an 80 integral flanged structure, whose flange forms a gutter seat, the heel part of which is perpendicularly arranged, a rib bent out from the heel part of said web, said rib being apertured, and a gutter catch formed 85 from said flange, the material of the remaining part of the structure coextensive with the catch being sheared off.

In testimony whereof, I have hereunto signed my name.

MATTHEW RUSSELL BERGER.
